*Fig. 6.*FIG. 1 is a front perspective view of a clock embodying my new design;

FIG. 2 is a top plan view of the clock shown in FIG. 1;

FIG. 3 is a front elevational view of the clock shown in FIG. 1;

FIG. 4 is a side elevational view of the clock shown in FIG. 1;

FIG. 5 is a rear elevational view of the clock shown in FIG. 1; and

FIG. 6 is a bottom plan view of the clock shown in FIG. 1.

The characteristic features of my design include the flat, narrow, bordering bezels of the octagonal portion of the clock and of the pendulum box which set forth the clock case and frontal piece of the pendulum box with

complete separate framing borders; the horizontal elongation of the pendulum box; and the scallop-bordered bowl, leaf, and solitary flower arrangement on the forward pendulum box surface.

I claim:

The ornamental design for a clock or similar article, substantially as shown and described.
